UNITED STATES PATENT OFFICE

ELTON A. POPE, OF OAKVILLE, CONNECTICUT, ASSIGNOR TO THE CHASE COMPANIES, INCORPORATED, OF WATERBURY, CONNECTICUT, A CORPORATION

DESIGN FOR A BATH-ROOM FIXTURE

Application filed May 6, 1932. Serial No. 43,732. Term of patent 7 years.

To all whom it may concern:

Be it known that I, ELTON A. POPE, a citizen of the United States, residing at Oakville, in the county of Litchfield and State of Connecticut, have invented a new, original, and ornamental Design for a Bath-room Fixture, of which the following is a specification, reference being had to the accompanying drawing, forming part thereof.

Fig. 1 is a front view of a bath-room fixture showing my new design;

Fig. 2 is a plan view of the same; and

Fig. 3 is a side view of the same.

I claim:

The ornamental design for a bath-room fixture as shown.

ELTON A. POPE.
